DESIGN FOR A RAZOR

John E. Doss, Jr., Newark, N. J., assignor to
A. Hager Bryant, Jr., Upper Montclair, N. J.

Application March 9, 1946, Serial No. 127,275

Term of patent 14 years

(Cl. D22—3)

To all whom it may concern:

Be it known that I, John E. Doss, Jr., a citizen of the United States and a resident of Newark, in the county of Essex and State of New Jersey, have invented a new, original, and ornamental Design for a Razor, of which the following is a specification, reference being had to the accompanying drawing, forming part thereof, in which—

Fig. 1 is a perspective view of a razor showing my new design.

Fig. 2 is a plan view thereof.

I claim:

The ornamental design for a razor, substantially as shown.

JOHN E. DOSS, JR.
